UNITED STATES PATENT OFFICE.

JACOB WILLIAMSON, OF CHICAGO, ILLINOIS.

DESIGN FOR A DISH.

No. 38,249.

Specification for Design.

Patented Sept. 25, 1906.

Application filed October 12, 1904. Serial No. 228,247. Term of patent 8½ years.

To all whom it may concern:

Be it known that I, JACOB WILLIAMSON, a citizen of the United States, and a resident of Chicago, in the county of Cook and State of Illinois, have invented a new, original, and ornamental Design for Dishes, of which the following is a specification, reference being had to the accompanying drawing, forming a part thereof.

The drawing represents a plan view of a dish, showing my new design.

I claim—

The ornamental design for a dish, as shown.

JACOB WILLIAMSON.
